DESIGN FOR AN ELECTRIC RECORD PLAYER OR SIMILAR ARTICLE

Irving Strauss, Bridgeport, Conn., and Gerald O.
Kaye, Forest Hills, N. Y.

Application May 26, 1945, Serial No. 119,753

Term of patent 3½ years

(Cl. D56—4)

To all whom it may concern:

Be it known that Irving Strauss and Gerald O. Kaye, citizens of United States and resident of Bridgeport, in the county of Fairfield and State of Connecticut, and resident of Forest Hills, in the county of Queens and State of New York, respectively, have invented a new, original, and ornamental Design for an Electric Record Player or Similar Article, of which the following is a specification, reference being had to the accompanying drawing, forming part thereof, and in which,

Fig. 1 is a perspective view of the electric record player embodying our new design; and

Fig. 2 is a top plan view thereof.

The other side of the record player is the same as illustrated and the rear and other side portions of the loud speaker or amplifier unit are plain.

We claim:

The ornamental design for an electric record player or similar article, substantially as shown and described.

IRVING STRAUSS.
GERALD O. KAYE.
